CLAIM

The ornamental design for a multi-head brush, as shown and described.

DESCRIPTION

FIG. 1 is an environmental exploded view of the multi-head brush, showing the new design;

FIG. 2 is a perspective view of the multi-head brush thereof;
FIG. 3 is a front elevational view of the multi-head brush thereof, the rear view being identical to the front view thereof;

FIG. 4 is a left side elevational view of the multi-head brush thereof;

FIG. 5 is a right side elevational view of the multi-head brush thereof;

FIG. 6 is a top plan view of the multi-head brush thereof; and,

FIG. 7 is a bottom plan view of the multi-head brush thereof. The broken lines shown in FIG. 1 depict environment and form no part of the claimed design. All other broken lines depict portions of the multi-head brush that form no part of the claimed design.

1 Claim, 4 Drawing Sheets
